UNITED STATES PATENT OFFICE.

GUSTAVE M. MINTON, JR., OF NEW YORK, N. Y.

DESIGN FOR AN ATOMIZER HOLDER.

Application filed August 4, 1928. Serial No. 27,708. Term of patent 3½ years.

To all whom it may concern:

Be it known that I, GUSTAVE M. MINTON, Jr., a citizen of the United States of America, residing in New York, county and State of New York, have invented a new, original, and ornamental Design for Atomizer Holder, of which the following is a specification, reference being had to the accompanying drawing, forming part thereof, in which—

Figure 1 is an elevation of the article, showing my new design, and

Figure 2 is a plan view of the same.

I claim:

The ornamental design for an atomizer holder as shown.

Dated at New York, N. Y., this 26 day of July, 1928.

GUSTAVE M. MINTON, JR.
